IGNITION APPARATUS

Ludvig P. Kongsted, Longmeadow, Mass., assignor to American Bosch Arma Corporation, a corporation of New York

Application January 25, 1955, Serial No. 483,873

4 Claims. (Cl. 310—70)

This invention relates to ignition apparatus for internal combustion engines or the like and has particular reference to a new and improved self-contained ignition apparatus or system which in its normal running operation does not employ breaker or contact points.

Contact points and breaker points as used in breakers have been a source of trouble due to burning or pitting of the points and have prevented magneto and battery ignition systems, which require such points, from rendering long uninterrupted service.

It is the primary object of the present invention to provide a new and improved ignition apparatus and system which utilizes contact points and breaker points for starting purposes only and therefore provides a new and improved ignition system or apparatus which is particularly adapted to provide long uninterrupted service.

Referring to the drawings:

Fig. 1 is a schematic wiring diagram of a form of the apparatus or system embodying the invention;

Fig. 2 is a side view of the apparatus embodying the invention;

Fig. 3 is an end view thereof taken from the drive end;

Fig. 4 is an end view thereof from the end opposite that shown in Fig. 3;

Fig. 5 is a sectional view taken on line 5—5 of Fig. 4, looking in the direction of the arrows;

Fig. 6 is a sectional view taken on line 6—6 of Fig. 5, looking in the direction of the arrows;

Fig. 7 is an end view of the breaker and condenser mechanism used for starting;

Fig. 8 is a top view of the rectifier;

Fig. 9 is a fragmentary view taken on line 9—9 of Fig. 5, looking in the direction of the arrows; and

Fig. 10 is a fragmentary view taken on line 10—10 of Fig. 5, looking in the direction of the arrows.

The present invention comprises a magnetic rotor sufficiently large to generate a current pulse which when fed into the primary circuit of a stepup transformer is sufficiently strong to generate a high voltage spark in a secondary winding without the use of breaker points and a condenser while in normal running operation.

In the present apparatus breaker points are used only at low cranking speeds in order to obtain the benefit of steep wave front pulses generated in normal magneto fashion, but such breaker and contact points are automatically cut out of the circuit at normal running speeds of the apparatus and thereby avoid wear and tear of the points and permit the apparatus to operate as a pulse generator.

Referring more particularly to the drawings wherein similar reference characters designate corresponding parts throughout, the apparatus shown embodying the invention comprises a housing 10 in which is journaled the magnetic rotor 11 which rotor comprises two independent magnets 13 located diametrically opposite. Each of these magnets has its set of laminated pole shoes 12 so arranged as to cause a reversal of flux through the

generating coils as the rotor sweeps past in proper spaced relationship and are so polarized that the direction of reversal of the flux is always the same.

The stator 14 is positioned relative to the magnetic rotor 11 and the stator 14 has the two generating coils 15 which are located for even firing at 90° apart with each of the generating coils 15 adapted to feed one-half the number of cylinders of the internal combustion engine or the like for which the apparatus is intended to supply ignition.

The distributor rotor 16 is journaled in parallel spaced relation relative to the magnetic rotor 11.

The distributor rotor 16 has the collector rings 17 adjacent its opposite ends and the contacts or inserts 17b which are positioned within rotor 16 with the surface of the inserts flush with the surface of the rotor. Each of the collector rings 17 is connected to one-half of the inserts or segments 17b through the connectors 18 and is adapted to supply current to its respective set or series of inserts.

The inserts or segments 17b are so positioned on the distributor rotor 16 as to engage the contact brushes 19 in proper sequence to feed the stepup transformer coils located at or near the engine spark plugs.

Each of the generating coils 15 feeds its respective collector ring 17 to which it is connected by a conductor 17a, and therethrough its half section of the inserts or segments on the distributor rotor.

The magnetic rotor 11 is operatively connected to the engine in the usual manner and the magnetic rotor 11 and distributor rotor 16 are operatively connected by means of the chain or timing belt drive 20 which engage sprockets 21 on rotor 11 and 22 on distributor rotor 16 respectively and such a drive insures proper relationship or timing and speed of rotation of distributor rotor 16 relative to magnetic rotor 11.

Each of the generating coils 15 is connected to its own rectifier 23, which rectifier is preferably of the selenium dry plate, to obtain a single unidirectional current pulse, as generated by the flux reversal, it is necessary to use a rectifier in the circuit so as to bypass the current pulses of opposite polarity which are generated. The rectifiers are connected in parallel or across the generating coil in such a manner as to block the maximum or useful current pulse and short circuit the other pulses of opposite polarity thus forcing the useful primary pulse to enter the primary winding of the stepup transformer.

Connected with each of the generating coils 15 is a condenser 24 each of which is connected to a breaker 25 which normally remains open rather than closed.

On the end of magnetic rotor 11 is provided the extension 26 on which is positioned the centrifugal governor mechanism 27 consisting of the centrifugal weights 28 on the pivot 29 which extends into slots 30 on actuating member 31 which has a cam portion 32 adapted to engage the sliding pins 33 for urging each of the breakers 25 into operation during each revolution of the magnetic rotor at low cranking speeds in proper timed relationship with the magnetic flux reversals of the rotor 11 and brush contact of the distributor 16.

When the speed of rotation of the magnetic rotor 11 is sufficient to insure a good current pulse without the use of the breakers, the centrifugal weights 28 will pivot to the position shown in dotted lines in Fig. 9 which causes rotation of member 31 relative to the rotor shaft and because of pin 35 in cam slot 34, on the rotation of member 31, the cam 32 is retracted to a position at which it cannot cause pins 33 to engage breakers 25 to cause the breaker points to contact on rotation of the magnetic rotor. It will thus be seen that the breaker mechanism 25 can only be caused to operate at low cranking speeds and that at higher operating speeds, the

centrifugal governing mechanism automatically ceases further operation of the breakers thereby completely avoiding all further wear and tear of the breaker mechanism and permits the apparatus to operate as a pulse generator during its normal running operation.

It should be understood that the number of generating coils and slot positions on the stator may be increased or decreased and the timed relationship of the magnet rotor and distributor rotor changed to suit the requirements of various engines according to the number of cylinders of the engine and whether it has two or four cycle operation. Likewise the number of magnets on the magnetic rotor may be varied to suit engine requirements and drive speed ratios.

In operation, the rotation of the magnetic rotor relative to the generating coils 15 supplies a properly timed current pulse through the collector or slip rings 17 to the various inserts or segments 17b by way of conductor 18. As the distributor rotor 16 and magnetic rotor 11 are driven in proper speed and timing relationship, current is supplied by each of the inserts 17b to its respective contact brush 19 which contact brushes are connected to the stepup transformer of sufficient strength or peak intensity to generate a high voltage spark in the secondary windings without the use of breaker points and condensers while in normal running operation.

It will be seen from the foregoing that the condensers 24 and breakers 25 are only employed at low cranking speeds beyond which they are automatically eliminated from operation at which time the apparatus functions as a magneto type of pulse generator without condensers and breaker points and which is capable of rendering long uninterrupted service due to the freedom from the inherent and well known difficulties obtained with breaker points during normal continuous operation of the device.

From the foregoing it will be seen that I have provided new and improved means for obtaining all of the objects and advantages of the invention.

I claim:

1. In a device of the character described, a stator, a magnetic rotor mounted for rotation relative to said stator, a distributor rotor, collector means on said distributor rotor and electrically connected to said stator, a plurality of contacts on said distributor rotor, contact members adjacent said distributor rotor and each being adapted to make electrical contact with its respective distributor rotor contact upon rotation of said distributor rotor and means for driving said magnetic rotor and distributor rotor in operative relation, contact means adjacent one of said rotors and means on said rotor for actuating said contact means and centrifugally operative means on said rotor for rendering said breaker contact inoperative except at cranking speeds.

2. In a device of the character described, a stator, a

magnetic rotor in operative relation with said stator, a distributor rotor having collector means electrically connected to said stator, said distributor rotor having contacts connected with said collector means and contact means adjacent said distributor rotor and adapted to be electrically connected with said contact means on said rotor upon rotation of said rotor and means for driving said distributor rotor and said magnetic rotor in operative relation, breaker means adjacent said magnetic rotor and means operatively connected to said magnetic rotor for actuating said breaker means and means automatically actuated by said magnetic rotor for rendering said breaker mechanism inoperative except at cranking speeds.

3. In a device of the character described, a stator, a magnetic rotor in operative relation with said stator, a distributor rotor having collector means electrically connected to said stator, said distributor rotor having contacts connected with said collector means and contact means adjacent said distributor rotor and adapted to be electrically connected with said contact means on said rotor upon rotation of said rotor, said magnetic rotor and distributor rotor being in spaced parallel relation and endless drive means connecting said rotors for effecting rotation thereof in predetermined relation, breaker means adjacent said magnetic rotor, means on said magnetic rotor for operating said breaker means and means for rendering said breaker means inoperative except at cranking speeds.

4. In a device of the character described, a stator, a magnetic rotor in operative relationship with said stator, a distributor rotor operatively connected to said magnetic rotor whereby said rotors will be rotated in predetermined relation, said distributor rotor having collector means adapted to be energized by said stator and magnetic rotor, said distributor rotor having contact means electrically connected to said collector means and contact members adjacent said distributor rotor and adapted to be electrically connected to said contact means on said distributor rotor upon rotation of said distributor rotor, breaker means adjacent one of said rotors and means on said rotor adjacent said breaker means for actuating said breaker means and means for rendering said breaker means inoperative except at low speeds.
